Primary Examiner — Kevin K Rudzinski*Assistant Examiner* — Clare Ann Gannon(74) *Attorney, Agent, or Firm* — Denis Khoo(57) **CLAIM**

The ornamental design for a shoe, as shown and described.

DESCRIPTION

FIG. 1 is a perspective view of a shoe showing my new design;

FIG. 2 is a front view thereof;

FIG. 3 is a rear view thereof;

FIG. 4 is a side view thereof;

FIG. 5 is a side view thereof;

FIG. 6 is a top view thereof; and,

FIG. 7 is a bottom view thereof.

All of the broken lines on the bottom of the shoe in FIGS. 2 and 7 represent a portion of the article that does not form a part of the claim.

All of the broken lines not on the bottom of the shoe in FIGS. 1-6 represent stitching which forms a part of the claim.

1 Claim, 7 Drawing Sheets(56)
